UNITED STATES PATENT OFFICE

142,260

DESIGN FOR A FAN PROPELLER

Bert Lee, Sacramento, Calif.

Application May 14, 1945, Serial No. 119,739

Term of patent 14 years

(Cl. D26—7)

To all whom it may concern:

Be it known that I, Bert Lee, a citizen of the United States, residing at Sacramento, in the county of Sacramento and State of California, have invented a new, original, and ornamental Design for Fan Propeller, of which the following is a specification, reference being had to the accompanying drawing, forming a part thereof.

Figure 1 is a front elevational view of a fan propeller, showing my new design; and

Figure 2 is an edge view of the fan propeller, partly in section.

Figure 3 is a fragmentary perspective view of the fan propeller.

I claim:

The ornamental design for a fan propeller, as shown.

BERT LEE.
